DOMESTIC REFRIGERATOR

Carl G. Vretman, Atlanta, Ga.

Application May 16, 1939, Serial No. 273,987

7 Claims. (Cl. 62—95)

This invention relates to refrigerators, and particularly to cooling elements for domestic refrigerators and the arrangement of the cooling elements in the refrigerator housing.

An object of this invention is to provide a cooling element and arrangement thereof which will provide a freezing compartment normally out of communication with the rest of the refrigerator chamber and which will cool the rest of the refrigerator chamber to the desired temperature without any part of the rest of the chamber being below freezing or frosting temperature, but in which the atmosphere and humidity of the rest of the chamber, that is, the food compartments, will not be in direct contact with the evaporator but will be only indirectly in heat transfer relation thereto through a liquid heat transfer chamber, whereby frost in the food compartments is eliminated and drying of the food compartments is reduced.

Another object of this invention is to provide an extremely simple arrangement of the cooling elements in the housing which will divide the inside of the chamber or box into a plurality of compartments which, by reason of the relative location of the cooling elements, will tend to maintain said compartments at different relative temperatures.

Another object of the invention is to provide a freezing unit which will not require a drip pan to catch such small quantity of moisture of condensation as may occur, and in which said moisture, if any, will not fall upon the contents of the refrigerator but will run down the side walls.

A further object of this invention is to provide a cooling unit of such construction that the absorption of heat from the compartments on one side thereof will be substantially uniform throughout all unit areas thereof, so as to avoid irregular freezing and accumulation of frost.

Still another object of this invention is to provide a refrigerator box or housing divided into several compartments which, when the door is closed, are completely and tightly sealed from each other so as to prevent interchange of atmosphere and temperature exchange, but which, when the door is open, will be open for free access thereto.

A further object of this invention is to provide a refrigerator having a plurality of compartments, one of which is a freezing compartment, in which the food compartments are cooled by the same cooling elements as the freezing compartment, but in which the atmosphere

and humidity of the food compartments will not have access to the freezing compartment, whereby frosting of the freezing compartment and drying of the atmosphere of the food compartments are reduced.

5 A still further object of the invention is to provide a freezing unit of a type which can be cleared of frost or ice or other adhering matter quickly and conveniently by scraping substantially plane, smooth surfaces and without the necessity of putting the refrigerating apparatus out of operation.

10 Still another object of this invention is to combine a flat evaporator with a flat plate or chamber containing liquid which does not freeze at the temperature to which it is to be subjected or is of a refrigerant nature, that is, a liquid capable of circulating or moving about actively due to small temperature differences, so 15 that the liquid serves as a heat transfer or distribution medium for making the temperature of the surface of the liquid plate opposite the evaporator substantially uniform and to maintain all parts of said surface above freezing or frosting temperature.

20 A further object of this invention is to enlarge the cooling surfaces effecting the storage compartments of the refrigerator so as to increase the heat transfer area and to thus reduce the intensity of coldness of said surfaces while obtaining at least equal heat transfer.

25 A still further object of this invention is to provide for removal of condensation from the cooling surfaces to a collecting vessel in a simple manner requiring no drip pan.

30 In the accompanying drawings which illustrate three embodiments of the invention by way of example only,

35 Fig. 1 is a side sectional view of a domestic refrigerator;

40 Fig. 2 is an elevational sectional view on the line II—II of Fig. 1;

45 Fig. 3 is a vertical side sectional view of a second embodiment;

50 Fig. 4 is an elevational sectional view of Fig. 3 on the line IV—IV thereof;

55 Fig. 5 is a side sectional view of a third embodiment of the invention; and

Fig. 6 is an elevational sectional view on line

50 VI—VI thereof.

In the drawings, numeral 1 indicates generally an insulated box having a door 2 at the front and supported above a compartment 3 for the refrigeration mechanism indicated generally by 55 numeral 4. The refrigeration mechanism may

be of any suitable type, such as a conventional mechanical compression and expansion type, or a gas absorption type. As the present invention does not directly concern the mechanism for compressing the refrigerant, this mechanism need not be particularly described herein, but is diagrammatically represented in the drawing as a conventional mechanical unit comprising a compressor, a condenser, a receiver, and connections for conducting the refrigerant to an expansion valve 5 located in close proximity to the evaporator. In Figs. 1 and 2 the cooling elements 7 and 8 may comprise evaporators 9 and 10 in the form of flat coils or else vacuum plates of more or less conventional character per se and liquid heat transfer plates 13 and 14 located on the top and bottom of the upper and lower evaporators 9, 10 respectively. The evaporators are preferably connected in series, and one of said evaporators, for instance, the lower evaporator 9, receives the expanding refrigerant from the expansion valve 5, and from said lower evaporator 9 the refrigerant passes through 11 to the upper evaporator 10, from which it then passes through return pipe 12 back to the compressor or the like.

The compartment 23 between the cooling elements 7 and 8 constitutes the coldest compartment of the refrigerator, which is used for making ice or frozen desserts, for keeping meat, or for other purposes where low temperatures are required. Freezing trays 17 are shown in the freezing compartment 23 in broken lines.

The liquid heat transfer plates or chambers are entirely closed and fit closely against the side and back walls of the refrigerator box and may be soldered or otherwise integrally connected with the walls or may have rubber sealing strips between the edges and walls in such manner as to prevent air or liquid from passing between their edges and the walls, and may be soldered, welded, cemented or otherwise integrally connected to the evaporators to prevent moisture from getting therebetween. The liquid plates are filled with a liquid which will not freeze at the temperature to which it is to be subjected, or which may be of a refrigerant nature. At the front edges of the liquid plates, resilient packings, such as rubber strips 18 and 19, are secured for sealing against the inside of the door when the door is closed, thus preventing passage of air or liquid.

The purpose of the liquid plates is to make the temperature on their sides opposite the cooling elements uniform, and possibly may retard heat transfer to such extent that said opposite sides may remain above freezing at all times. It is apparent that along the surfaces of the vacuum plates the portions closely adjacent an interior pipe will be colder than the portions adjacent the spaces or gaps between the interior pipes. This is undesirable, as it would cause freezing of ice or frost in ridges along the colder portions. However, this unevenness of temperature cannot penetrate through the liquid plates but, due to the action or local movement within the liquid, is made uniform at the opposite surfaces.

The division walls forming the coldest compartment are thus constituted by the cooling elements which include the evaporators, which may be vacuum plates, and liquid plates which are smooth and substantially plane on their surfaces. However, the lower surface of the lower liquid plate is preferably made to slope slightly downwardly from a central line toward the sides

(Fig. 2) or from the front towards the rear so that moisture of condensation or melted frost, if any, will run to the sides or back instead of dropping upon the contents of the lower compartment.

The walls of the freezing compartment are located in the refrigerator at any desired location depending principally upon the relative temperatures desired to be maintained in the upper and lower compartments. If it is desired that the upper compartment be colder than the lower compartment, the division walls constituted by the cooling elements and liquid plates should be located considerably closer to the top than to the bottom. The upper compartment thus being the smaller requires less cooling to attain the lower temperature but, due to the fact that heat tends to rise, the efficiency of heat transfer from the lower compartment to the lower liquid plate is higher than from the upper compartment to the upper liquid plate. This tends to make the lower compartment the colder so that it is necessary that the upper compartment be made even smaller than would otherwise be the case, in order that it shall have the lower temperature of the two. It will be observed that in the illustrated embodiment the upper compartment is shown as being only about half the size of the lower compartment. This relation of sizes can be varied at will and if it is desired that the lower compartment be the colder, it is only necessary to arrange the cooling elements at a lower position.

In operation, the freezing compartment, being located directly between the two evaporators 9 and 10, is maintained at a low temperature for freezing its contents. The upper compartment 21 being comparatively small is the next coldest compartment. The floor of this compartment which is constituted by the liquid plate 14 in contact with vacuum plate 10, serves to cool the compartment, and the liquid plate serves to make the temperature uniform over the entire area of the floor. As the upper surface of the liquid plate is smooth, accumulations of frost, if any, may be scraped off the plate so that it will hardly ever be necessary to turn off the refrigeration apparatus for defrosting. In a similar way the lower compartment 22 is cooled by liquid plate 13, but the compartment 22 being larger than the upper compartment is maintained at a higher temperature. However, the relative temperature can be changed by changing the position of the cooling elements so that the relative sizes of the compartments is changed. If moisture should ever be present on the lower face of liquid heat transfer plate 13, it will run to the sides or back and down the side walls or back wall instead of dropping upon the contents of the compartment, this action being due to the lateral or rearward downward slope of the lower face of said plate.

In the embodiment illustrated in Figs. 1 and 2 two evaporators connected in series have been disclosed, but, if desired, one of these may be omitted, in which case a liquid heat transfer plate or a plain sheet metal plate will serve as the partition for the freezing compartment.

Furthermore, as a further alteration, one or both of the evaporators may extend only partially across the chamber, but in this case the liquid or metal heat transfer plates should extend the entire width and serve as the partitions.

In the embodiment illustrated in Figs. 3 to 6 inclusive the outer shell of the refrigerator

housing and the refrigeration mechanism located in the lower part of the refrigerator may be similar to that described in connection with Figs. 1 and 2. However, the cooling elements are considerably modified and will therefore be described in detail.

In the embodiment of this invention shown in Figs. 3 and 4 each cooling element comprises an evaporator 26, of different shape from that shown in Figs. 1 and 2. The evaporator is of somewhat reduced transverse extent and is composed of upper and lower plates which do not extend entirely to the back of the chamber or entirely across the lateral extent of the chamber divided by the cooling elements. As is clear from Fig. 4, the upper and lower plates 27 and 28 respectively of evaporator 26 are joined together at one edge by a vertical plate portion 29. The upper surface of lower plate portion 28 is preferably level and may serve for supporting 20 ordinary ice trays 30. For the purpose of uniformly distributing the cooling effect of the evaporator 26, particularly that of the vertical portion 29 thereof, and for dividing the interior of the housing into compartments, liquid plates 32, 33 and 34 are provided. Liquid plate 32 may extend vertically the entire extent of the chamber and entirely from front to rear. The top, bottom and rear edges are preferably air-tightly joined to the walls of the chamber by rubber packing strips 31 or by soldering or the like and the front edge is provided with an elastic strip 35 which seals against the door when closed. The vertical liquid plate serves as a partition dividing a compartment 31 from the chamber and also, as mentioned above, serves to spread out the cooling effect of the vertical part 29 of the evaporator so that no part of the surface of the vertical liquid plate adjacent compartment 37 will be below freezing temperature and frosting will not occur on this surface.

Liquid plate 33 extends over the upper part 27 of the evaporator and is preferably tightly joined to this part of the evaporator, for instance by soldering, to improve the heat transmission and to prevent moisture or ice getting between the adjacent surfaces thereof. The liquid plate 33 preferably extends entirely from front to rear of the chamber and entirely across the chamber from the liquid plate 32 to the opposite wall and thus divides off an upper compartment 38 in the chamber. The front edge is preferably provided with an elastic strip 39 for sealing against the door and the side and rear edges may be soldered or sealed by rubber strips 31 to the adjacent walls. The upper surface of liquid plate 33 is corrugated for increasing the area of heat exchange to the air in compartment 38. The liquid plate will distribute the cooling effect so that no part of its upper surface will collect frost, but being generally cooler than the air in compartment 38, there may be a certain amount of condensation on the surface. In order to drain off this condensation, the plate is made to slope downwardly rearwardly and at the rear a drain pipe 40 extends downwardly to a collecting vessel 42 in the lower portion of the refrigerator or to a gutter which leads to the collecting vessel. Since it is undesirable for dishes or the like containing liquid to rest on a sloping surface, a level grill 41 is placed in the upper compartment close to the liquid plate 33 for supporting the contents of the compartment.

As previously stated, the upper surface of the lower portion 28 of the evaporator 26 is level on

its upper surface, and its lower surface is in contact with or soldered to the flat upper face of a liquid plate 34 which may be similar to the upper liquid plate 33 in that it divides the chamber horizontally and is sealed against the door by an elastic sealing strip 44 and against the side and rear walls by soldering or rubber packing 31, but, instead of the upper surface being corrugated, the lower surface is corrugated. The lower surface of this plate slopes downwardly rearwardly so that any moisture that may accumulate will run to the rear and down the rear wall to a gutter 45 which collects the moisture and conducts it to the collecting vessel 42 previously mentioned.

Instead of the liquid plates 33 and 34 having corrugated surfaces, the area of heat transfer thereof may be increased by providing a series of fins.

In the embodiment of the invention illustrated in Figs. 5 and 6 the liquid plates are not used for dividing the chamber transversely, but in this case the evaporator is made so that the pipes extend around a freezing chamber 50 and are enclosed by inner and outer box-like plates 52 and 53 and the evaporator is surrounded by a box-like liquid plate 54 which may extend forwardly and rearwardly. The outer walls may be corrugated or provided with fins to increase the heat transfer and, if necessary, the rear may have a liquid heat transfer plate secured thereto to increase the area of transfer to ensure that no part of the outer surface is below freezing in order that no frosting shall occur. If desired, the front end may be provided with a hinged door to close off the interior and prevent circulation of air.

I claim:

1. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container, filled with liquid which will not freeze at the temperature to which it is to be subjected, said flat liquid container being located on the side of said evaporator plate toward the cold storage compartment for distributing the cooling effect of the evaporator over the surface of the liquid container opposite the evaporator, said container being entirely closed to the refrigerant, the surface of said liquid-containing chamber toward said cold storage compartment being extended beyond the limits of the evaporator to increase the area of heat transfer.

2. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber and a flat container closed with respect to the refrigerant, said container being filled with liquid which will not freeze at the temperature to which it is to be subjected, said container being located on the side of the evaporator plate toward the cold storage compartment for uniformly distributing the cooling effect of the evaporator over the surface of the liquid container opposite the evaporator, the surface of said liquid-containing chamber toward said cold storage compartment being corrugated to increase the area of heat transfer.

3. In a refrigerator, walls and a door forming

a chamber, a pair of flat cooling elements extending horizontally entirely across the chamber and spaced apart from each other so as to form a freezing compartment therebetween and upper and lower storage compartments above and below respectively, said cooling elements including flat evaporators and flat liquid-containing chambers adjacent said evaporators on the sides thereof adjacent the upper and lower compartments respectively for eliminating temperature differences in the cooling surfaces of the cooling elements, the upper surface of the upper liquid chamber sloping downwardly rearwardly, and a drain pipe leading from the rear edge of said upper surface for carrying away condensation liquid.

4. In a refrigerator, walls and a door forming a chamber, a pair of flat cooling elements extending horizontally entirely across the chamber and spaced apart from each other so as to form a freezing compartment therebetween and upper and lower storage compartments above and below respectively, said cooling elements including flat evaporators and flat liquid-containing chambers adjacent said evaporators on the sides thereof adjacent the upper and lower compartments respectively for eliminating temperature differences in the cooling surfaces of the cooling elements, the lower surface of the lower liquid chamber sloping downwardly rearwardly, and a sloping gutter extending across the rear wall of the lower compartment near the bottom thereof for collecting condensation water running down said rear wall.

5. In a refrigerator, insulated walls and a door forming a refrigeration chamber, a vertically extending flat chamber containing liquid extending forwardly and rearwardly in said refrigeration chamber dividing off a side storage compartment in said refrigeration chamber, an evaporator having a vertically extending wall adjacent an intermediate part of said vertical liquid chamber, said evaporator also having horizontally extending upper and lower evaporator plates spaced apart vertically and substantially horizontally extending flat liquid-containing chambers above

and below said upper and lower evaporator plates respectively and in close contact therewith, said horizontally extending liquid-containing chambers extending entirely across the refrigeration chamber laterally and forwardly and rearwardly between the vertically extending liquid-containing chambers and the insulated walls of the refrigeration chamber except in the compartment divided off by said vertical liquid-containing chambers, whereby said evaporator and liquid-containing chambers form a freezing compartment and food storage compartments, the walls of which storage compartments are maintained at a uniform temperature by the heat distributing effect of the liquid-containing chambers.

6. In a domestic refrigerator, walls forming a chamber, a cooling element in said chamber dividing off a part of said chamber as a freezing compartment while the remainder serves as a cold storage compartment, said cooling element comprising an evaporator in the form of a flat plate toward the freezing chamber, and also a flat container, filled with liquid which will not freeze at the temperature to which it is to be subjected, said flat liquid container being located on the side of the evaporator plate toward the cold storage compartment, said liquid container having a portion extending beyond the evaporator liquid container to increase the area of heat exchange so as to distribute the cooling effect of the evaporator over the surface of the liquid container opposite the evaporator plate.

7. In a domestic refrigerator, walls and a door forming a chamber, a cooling element located in said chamber and comprising horizontal and vertical evaporator plates forming a box-like freezing compartment, horizontal and vertical liquid-containing plates adjacent and outside said evaporator plates for distributing the cooling effect of the evaporator plates evenly over the outer surface of the liquid plates so as to maintain the surfaces in contact with the atmosphere of the chamber outside of the freezing compartment at a uniform temperature.

CARL G. VRETMAN.
